UNITED STATES PATENT OFFICE

98,465

DESIGN FOR A COMBINED CIGARETTE HOLDER AND ASH RECEIVER

William Berner Ulmer, Pottsville, Pa.

Application November 8, 1935, Serial No. 59,455

Term of patent 14 years

To all whom it may concern:

Be it known that I William Berner Ulmer, a citizen of the United States, residing at Pottsville, in the county of Schuylkill and State of Pennsylvania, have invented a new original, and ornamental Design for a Combined Cigarette Holder and Ash Receiver, of which the following is a specification, reference being had to the accompanying drawing, forming part thereof.

I claim:—

The ornamental design for a combined cigarette holder and ash receiver, as shown.

WILLIAM B. ULMER,
